UNITED STATES PATENT OFFICE.

FREDERICK E. WALDEN, OF WORCESTER, MASSACHUSETTS, ASSIGNOR TO BOSTON WRENCH CO., A CORPORATION OF MASSACHUSETTS.

BOTTLE-CAP.

1,250,534.

Specification of Letters Patent. Patented Dec. 18, 1917.

Application filed September 6, 1913, Serial No. 788,462. Renewed May 16, 1917. Serial No. 169,116.

To all whom it may concern:

Be it known that I, FREDERICK E. WALDEN, a citizen of the United States, and a resident of the city and county of Worcester and 5 Commonwealth of Massachusetts, have invented certain new and useful Improvements in Bottle-Caps, of which the following is a full and exact description.

The object of this invention is the construction of a cap or cover for bottles and the like, which will normally keep the latter tightly closed, but can at will be opened by the pressure of the thumb for pouring out more or less of the bottle's contents, and 10 upon the release of the thumb therefrom will immediately close; and which, moreover, by a more pronounced thumb-pressure, will receive a wide-open position, and will retain the same until the cap is given a slight movement back toward the bottle-mouth. Another object of this invention is the construction of a bottle cap which can be employed for bottles sealed by what are termed "crown seals," and can then be put 15 in the place thereof for temporary closure. A further purpose is the construction of a bottle cap composed of a minimum number of parts, at a minimum cost, and which can readily be applied to bottles of different sizes 20 and shapes.

Referring to the drawings forming part of this specification, Figure 1 is a side elevation of the upper part of a bottle showing my cap in position thereon and closing it. Fig. 2 is a side sectional view of the same, showing the cap sufficiently opened to permit the bottle contents to be poured out, and ready to fly back when released. Fig. 3 is a side view of the same, showing the cap wide 25 open. Fig. 4 is an approximately plan view of the cap. Fig. 5 is a plan view of the helical spring which controls the cap. Fig. 6 shows the cap used for removing a crown seal. Fig. 7 is a sectional view.

The great majority of bottles designed for the reception of tonics, beer and the like, are formed with a bead 1 about their mouths, and a shoulder 2 a short distance below such bead, such distance varying from an inch to 30 five-eighths. The cap 3, which is preferably provided with a yielding disk 4 for rendering the closure more nearly air-tight, is formed with an extension 5 preferably integral therewith. In this extension is a laterally extended recess 6 designed to receive

the slender helical spring 7 whose ends are fastened together to make a circle, as shown in Fig. 5. This circle is made small enough to compel it to elongate in order to reach around a bottle-neck and through said recess. 60

The side wings 9 of said extension are given shoulders 10, which by rocking against the surface of the bottle neck, act as a fulcrum to permit the cap to be elevated from its seat on the bottle-mouth by a downward pressure applied to the terminal portion of said extension, as shown in Fig. 2. These shoulders are so positioned that the pull of the helical spring against the bottom of said recess acts to rock the cap back firmly to its 70 closed position.

The extension 5 has its side wings formed with another pair of shoulders 11 so disposed that by rocking the cap over to the wide-open position illustrated in Fig. 3, the pull 75 of the helix will act to hold the cap securely in such position. The bottle-mouth being thus entirely unhindered by the cap, the bottle can be readily refilled; after which a tap against the cap will cause it to swing 80 past its fulcrum and snap back upon the mouth.

It is evident that the helix serves both to attach the cap to the bottle, and to fit any usual variations in diameter of its neck; and 85 also to confine the cap upon the bottle mouth equally well, whatever the distance of the shoulder 2 below the bottle-mouth. It further serves as the hinging member for the cap; the means for swinging the cap down 90 upon the mouth, and also the means for holding the cap wide open.

For enabling the cap and its extension to be used for the removal of sealing caps, such as the crown seal, from the bottles, said extension is formed with a wide slot 12 which is adapted to be engaged beneath the crimped edge of the crown seal, as shown in Fig. 6, and by an upward pull upon the cap 3 to pry the crown seal off from the bottle. 100

Another very important use for this cap is for employment as salt and pepper shakers. By dispensing with the disk 4 and forming the cap with several small holes 13, as shown in Fig. 4, the same can be applied 105 to salt and pepper bottles, and used in the customary manner. The great advantage thereby given is that of a time saver in refilling the containers, inasmuch as the cap can be so readily thrown into its vertical 110

wide-open position and filled without delay. This is especially desirable at summer hotels and large restaurants where time cannot be wasted in the laborious, and sometimes almost impossible effort, of unscrewing the screw-caps now in use for salt and pepper shakers.

What I claim as my invention is:

1. A closure for bottles and the like comprising a cap having a projection extending rigidly from the periphery thereof in a direction substantially at right angles to the plane of the cap, and a resiliently extensible ring clasping the neck of the bottle for which said cap is designed and engaging said projection, the latter being formed with a shoulder resting against the bottle-neck slightly farther from the cap than is the point of said ring's engagement therewith, to cause the pull of said resilient ring to press the cap down upon the bottle-mouth.
2. A closure for bottles and the like comprising a cap having an extension formed with a deep recess, and a helical spring formed into a ring resiliently clasping said extension in said recess and also the neck of the bottle used therewith.
3. A closure for bottles and the like comprising a cap having an extension, and a resiliently extensible ring engaging said extension and clasping the neck of the bottle used therewith, said extension having shoulders coacting with the surface of the bottle neck at successively different points.
4. A closure for bottles and the like comprising a cap having a rigid projection formed with a shoulder the part of said projection between the shoulder and cap being substantially at right angles to the plane of the cap, and the remainder of the

projection being angularly disposed, and a resiliently extensible ring engaging said projection and the neck of the bottle for which the same is designed, said shoulder and angularly disposed portion of the projection coming against the side of the bottle neck and coacting with said ring to support the cap in a wide open position.

5. A closure for bottles and the like comprising a cap having an extension, and a resiliently extensible ring engaging said extension and clasping the neck of the bottle used therewith, said extension being formed with a thumb piece and two pairs of shoulders coacting with the surface of the bottle neck, one pair of said shoulders permitting the pivotal return of the cap to the bottle-mouth, and the other pair of shoulders serving, upon a lower depression of said thumb-piece, to hold the cap wide open.

6. The combination with a bottle having a crown seal strongly closing it, the crown seal being formed with a crimped edge engaging the outer periphery of the bottle-mouth, of a cap for temporarily closing the bottle after the crown seal has been removed, said cap being formed with a rigid projection extending radially from the cap, said projection having a transversely disposed slot adapted to be engaged with the crimped edge of said crown seal and the top surface of the latter for enabling the crown seal to be pried off from the bottle.

In testimony that I claim the foregoing invention, I have hereunto set my hand this 15th day of August, 1913.

FREDERICK E. WALDEN.
